CLAIM

We claim the ornamental design for an oral irrigator handle, as shown and described.

DESCRIPTION

FIG. 1 is a front isometric view of an oral irrigator handle.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken line showing oral irrigator tip illustrates environment that forms no part of the claimed design. All other broken lines illustrate portions of the oral irrigator handle that form no part of the claimed design.

1 Claim, 4 Drawing Sheets(56)
